PROCESS OF SPINNING FLAX AND
SIMILAR FIBERSArthur Job, Providence, R. I., assignor to Sils
Corporation, a corporation of Delaware

Application December 2, 1941, Serial No. 421,263

7 Claims. (Cl. 57—156)

The invention relates to the art of spinning yarn and more particularly to an improved method of spinning of flax and similar fibers, a machine for carrying same into practice, and the product resulting therefrom.

With particular reference to the spinning of flax in the production of linen yarns it has heretofore been the custom to utilize the fibers of partly matured flax plants, grown especially for fibers and not for seed. Flax plants intended for such use are generally planted in the spring of the year and are harvested usually some time in the following July. At this stage the flax plants are not fully matured and the fibers thereof have not yet fully developed. The flax straw resulting from such partly matured flax plants is then subjected to the so-called retting, or in other words, is immersed in water for a definite period as for instance ten days. This retting of the flax straw develops a bacterial process which serves to dissolve the pectins or gum located externally of and between the fibers and thereby loosens the fibers by degumming the straw as stated. The aforesaid retting does not affect the internal gum located between the fibrils so that the latter are not degummed at all. At the end of the retting step the degummed straw stalks are dried and in this condition are decorticated to break up the pith and separate it from the fibers. For high grade linens the expensive hacking process is used and for low grade linens and tows softeners are used. The resulting chips of broken pith are generally from one half to two inches in length, and a substantial part of said broken pith chips remain attached to the fibers which themselves are often broken by this decortinating treatment.

The invention has for its object to provide a novel process of producing linen yarn from the fibers of fully matured flax plants grown primarily for the production of flax seed and heretofore otherwise regarded as waste having little or no commercial value.

The invention contemplates a novel process in which the objections incidental to the existing methods such as the onerous, expensive and slow step of retting are avoided and whereby the time element is reduced to a minimum.

Furthermore, the invention has for its object to provide a novel process whereby the external gum between the fibers and the internal gum between the fibrils are both partly removed to provide partly degummed flax at a certain intermediate point of the spinning process, particularly when in the form of a roving.

Another object of the invention is to provide a novel linen yarn made from the fibers of fully matured flax plants and possessing all of the inherent characteristics of existing linen yarns of the tow type to an equal or superior degree.

The invention further contemplates a novel spinning machine of simple construction for carrying out the novel process and for spinning the novel linen yarn in an efficient manner.

10 Other objects and advantages of the invention will appear from the description hereinafter and the features of novelty will be pointed out in the claims.

In the accompanying drawings which illustrate examples of the invention without defining its limits,

Fig. 1 is a diagrammatic view showing the various steps of the novel process;

Fig. 2 is a fragmentary front elevation of a 20 novel spinning machine for spinning the novel yarn;

Fig. 3 is a sectional elevation thereof on the line 3—3 of Fig. 2;

Fig. 4 is an enlarged fragmentary detail view 25 of said spinning machine;

Fig. 5 is a detail view of one of the drawing cylinders or rolls included in the novel spinning machine, and

Fig. 6 is a detail view of a novel spool on which 30 the roving is wound in the form of cheeses to permit the latter to be easily removed at will.

In the production of the novel linen yarn the flax plants which heretofore have been grown primarily for the production of flax seed, are 35 planted preferably in the spring of the year and are harvested when the plants with the seed therein have fully matured which generally occurs at the end of August or the beginning of September after planting. The harvested flax plants are dried and threshed in any conventional manner to recover the seed, and the resulting flax straw is decorticated in a special manner, for instance, by being passed through a breaker A to preserve the fibers and to remove the pith. The decortication of the straw may be accomplished by any appropriate means.

The fibers resulting from the aforesaid decortication of the flax straw are carded, for instance, by being fed into a conventional flax carding machine B, to eliminate the major part of any remaining pith chips and any short fibers as well as dirt. The carding of the fibers forms the latter into slivers which are fed into a conventional drawing frame C' for doubling to convert a plurality of slivers, as for instance, three or four

slivers into one sliver or ribbon in the well-known way.

The sliver from the drawing frame C' is preferably combed in a special and novel manner preferably by means of a comber D which forms the subject matter of another application to be filed by me. After having been combed as stated, the resulting sliver is put through conventional drawing frames in a plurality of successive steps, as by being passed through three drawing frames 10 C², C³, and C⁴, and is then fed into a conventional roving frame E and the roving is angularly wound on spools to form what are technically known as cheeses. The spools of the roving frame preferably are however specially constructed to permit 15 the ready removal of the cheeses therefrom for chemical treatment. For instance, one end flange a of the spools b may be removably connected with the latter by means of a bayonet joint c, as shown in Fig. 6.

The chemical treatment above referred to may be carried out in a conventional dying kier F for yarn, and consists in boiling the cheeses in an alkaline solution with or without pressure for a predetermined period of time, as for instance, approximately one hour. In practice it has been found satisfactory to use about twenty-five pounds of caustic soda for each one hundred pounds of roving, with about fifteen pounds of caustic soda for each one hundred pounds of roving producing 20 excellent results. The application of the aforesaid caustic treatment to the cheeses at this stage of the spinning process is of importance to the performance of the fibers in the final steps of the spinning operation. The caustic treatment of the cheeses is carried to a point where the fibers are degummed so that under a heavy pull the cells of the fibrils will glide on one another. Incidentally the fibers will be partly bleached by removing some of the brown and green coloring 25 therefrom. The treated cheeses are then washed in hot water containing a small quantity of Na₂CO₃ to wash out the caustic. After having been washed the cheeses are put into a bath of hot water, preferably rendered slightly alkaline and preferably mounted on the spinning machine G and having a temperature such as to maintain the gum remaining in the fibers in a soaked and 30 plastic condition. It has been found that hot water having a temperature ranging from 150° F. to 160° F. produces the desired results.

At this point it may be stated that there are two conventional methods of spinning: A dry method and a wet method. In the conventional dry method the roving is simply taken from a dry spool and spun while dry. The conventional wet method consists in taking the same dry spool and passing the roving therefrom through a bath of water before it reaches the drawing cylinders. The wet method of spinning is superior because it produces a smoother and somewhat stronger 35 yarn than is obtained with this dry method of spinning. It is to be distinctly understood, however, that as a result of the retting to which the flax plant has been subjected the conventional linen roving which passes through the aforesaid processes of spinning has practically no gum between the fibers whereas the gum between the fibrils is not dissolved at all in the short passage through the bath.

In the instant case on the contrary both the fibers and the fibrils are partially degummed and intentionally so (i. e., the gum is dissolved), and the wet method of spinning and the drawing step thereof are fundamentally different. In carrying

out the present novel method of spinning, the rovings are unwound from the immersed cheeses and by means of feed rolls and drawing rolls in contiguous relation in the spinning machine G the cells in contradistinction to the fibrils are subjected to intensive drawing forces whereby the partly gummed cells and fibers are caused to effectively glide on one another. In actual practice the drawing rolls are of a relatively larger diameter than the feed rolls because of the fact that they have to be strong enough to resist the stresses due to the large weight they have to support. The intensive drawing action is effected over a comparatively short distance as for example two inches, or, in other words, less than the length of the greater number of fibers being fed to the drawing rolls; that is to say, the fibers being fed and drawn are longer than the distance between the points of contact between the drawing instrumentalities. It is to be noted that in the conventional methods of spinning flax the drawing forces are exerted on the fibers, and not on the cells as in the instant novel method, and the distance between drawing and feed rolls is greater than the longer fibers contained in the roving. Thus, the conventional spinning machines have a distance of at least eight inches, usually nine to twelve inches, between the bight of the feed rolls and the bight of the drawing rolls whereas in the new spinning machine the distance between said bights indicated by the lines A—A and B—B in Fig. 4, is less than about four inches and is preferably about two to about three inches. As a result of the novel procedure the intensively drawn fibrils and cells being still gummy stick to each other and as the spinning operation is completed provide a superior partly degummed linen yarn made from flax fibers of a type which heretofore has been considered as unfit for such purpose and generally has been regarded as a by-product of flax seed producing flax plants and having little or no commercial value.

Subsequent to the spinning operations the spun 45 partly degummed yarn preferably after having been dried for instance in a suitable drying oven, may be woven into fabric on a suitable loom H. In some instances the woven fabric of partly degummed yarn may be fully degummed in a suitable bath I, or its equivalent.

The spinning operations heretofore described may be performed in any convenient manner and by means of any suitable mechanism and 50 preferably are carried out by means of the novel ring spinning machine illustrated in Figs. 2, 3, 4, and 5 of the drawings.

The spinning machine, as shown in Figs. 2 and 3, comprises a suitable frame 10 on which a tank or receptacle 11 is supported in any convenient manner. The tank 11 is designed to contain hot water which constitutes the bath in which the cheeses 12 are put after having been washed as previously described herein. The cheeses 12 which are composed of roving wound angularly to hold their form, are rotatably supported in the tank 11 which is provided with a plurality of upright spindles 13 for this purpose, to enable the slivers to be readily withdrawn from said cheeses 12 as the spinning proceeds. A cover 14, preferably removable by means of handles 15 or at least movable to an open position at will serves as a closure for said tank 11, which is provided interiorly with grooved guides 16 of porcelain or other suitable material, as shown in 75 Figs. 2, 3, and 4. Additional similar guides 17

are mounted on brackets 18 exteriorly of the tank 11 in contiguous relation to exit openings 19 with which said tank 11 is provided as illustrated in Figs. 2, 3, and 4.

The illustrated spinning machine includes duplicate drawing units located at opposite sides thereof in predetermined number of groups dependent upon the size of the spinning machine. As the drawing units are duplicates of each other, it is only necessary to describe the elements of one complete unit which will apply also to all of the others.

As illustrated, each drawing unit consists of two associated pairs of drawing rolls conveniently mounted on the frame 10 in the preferred manner to be more fully set forth hereinafter. The aforesaid rolls comprise feeding rolls 20 and 21 which may correspond to the conventional feeding rolls of spinning machines, and drawing rolls 22 and 23. As shown in Fig. 2 of the drawings, the means whereby the feed roll 20 and drawing roll 23 are mounted in the machine comprises shafts 24 and 25 journaled in main bearing members 26 and auxiliary bearing brackets 27. The feeding roll 21 is carried by a shaft 21^a which is journaled in the main bearing members 26, and both feeding rolls 20 and 21 are preferably grooved lengthwise as diagrammatically illustrated in Fig. 4, the grooves being relatively shallow and of easy undulating form in cross-section in contradistinction to sharp deep serrations for the purpose to be more clearly set forth hereinafter. The feeding roll 21 may be mounted on the shaft 21^a or said feeding roll 21 and its shaft 21^a may constitute integral parts of each other fabricated from suitable material. The aforesaid is true also of the feeding roll 20 and shaft 24, which roll 20, however, may be otherwise constructed as for instance in the form of a cylindrical shell.

The main bearing members 26 are secured to and extend upwardly at spaced intervals from a cross-beam 28 suitably fixed in the frame 10, and the auxiliary bearing brackets 27 are located between the main bracket members 26 and are carried by a supporting bar 29 which itself is supported by said bearing members.

For the purpose to be more fully set forth hereinafter the shafts 24 and 25 preferably are mounted so as to permit the rolls 20 and 23 to shift toward and away from the respective associate rolls 21 and 22. For instance, the shafts 24 and 25 may have their opposite ends of reduced diameters to constitute trunnions 24^a and 25^a rotatably seated in preferably inclined bearing recesses 30 with which the bearing members 26 and bearing brackets 27 are provided. In the arrangement illustrated in the drawings each shaft 24 carries two feed rolls 20 in axially spaced relation and each shaft 25 has two correspondingly spaced drawing rolls 23 mounted thereon, it being understood that each roll 20 and each roll 23 constitutes part of adjacent and separate drawing units.

In the novel spinning machine illustrated in Fig. 4, the drawing roll 22 is much larger in diameter than the conventional drawing rolls of spinning machines for short fibers, which conventional drawing rolls generally correspond in diameters to the feeding rolls; in the instant machine, the drawing roll 22 is accordingly considerably larger in diameter than the feeding rolls 20 and 21, as shown in Figs. 3 and 4. The drawing roll 22 of each pair of drawing rolls consists preferably of a metal shell *d* mounted on a heavy steel shaft or driving cylinder 31 which is 75

suitably supported in the machine as by being mounted in the bearing members 26. The shell *d* of the drawing roll 22 is grooved lengthwise, as shown in Figs. 4 and 5, the grooves being of any conventional nature capable of providing the desired gripping action without injury to the fibers. The associated drawing roll 23 is covered with a yielding resilient or elastic material, preferably a very hard rubber, and is arranged to engage the co-operating drawing roll 22 peripherally in such a manner that an efficient grip will be developed on the fibers without injury thereto. At the same time, the drawing roll 23 exerts a heavy pressure, for instance, in excess of fifty pounds on the contiguous drawing roll 22. To develop the aforesaid pressure the trunnions 25^a of the roll 23, as previously stated, are movably mounted in the bearing recesses 30 of the bearing members 26 and the shafts 25 are provided at an intermediate point with circumferential grooves 32 for the reception of the hooked ends of bi-partite links 33 which include turnbuckles 34 and are pivotally connected at 35 with one end of rocking members 36. Additional bi-partite links 37 are pivotally connected at 38 with the other end of the rocking members 36 and are in hooked engagement with annular grooves 39 provided at intermediate points on the shafts 24 of the feeding rolls 20, said links 37 including turnbuckles 40 as illustrated in Figs. 2, 3, and 4. The rocking members 36 are pivotally connected at 41 with one end of links 42 preferably in unsymmetrical relation thereto, the other ends of said links 42 being pivotally connected at 43 with levers 44 in off-set relation thereto. The levers 44 in turn are fulcrumed at 45 upon brackets 46 mounted upon cross-beam 28 of the frame 10, the levers 44 being provided with a plurality of notches 47 in proximity to their free ends in which notches 47 counterweights 48 are suitably suspended.

With this arrangement the counterweights 48, acting on the levers 44, links 42, rocking members 36 and links 33 and 37, serve to draw the rolls 20 and 23 into engagement respectively with the rolls 21 and 22; because of the unsymmetrical location of the rocking members 36 on the links 42 the force developed by the counterweights 48 is exerted mainly on the drawing rolls 23 and cause the latter to exert the aforesaid heavy pressure on the associated drawing rolls 22.

Suitable means operable at will is provided for relieving the pressure of the rolls 20 and 23 on the associated rolls 21 and 22 respectively. In the illustrated example, this means comprises rods 49 slidably mounted in guides 50 on the frame 10 for vertical movement beneath and in registry with the levers 44. The rods 49 are pivotally connected at 51 with foot treadles 52 fulcrumed at 53 upon the frame 10. Obviously as the treadles 52 are depressed at their free ends, the rods 49 will be adjusted upwardly in the guides 50 into engagement with the levers 44 from below. As the pressure on the treadles 52 is continued, the rods 49 accordingly will swing the levers 44 upwardly on the fulcrums 45 and lift the counterweights 48 to thereby neutralize the effects thereof on the linkage and consequently relieve the drawing rolls 22 from the pressure of the associated drawing rolls 23; at the same time the feeding rolls 21 will be correspondingly relieved of the pressure of the associated feeding rolls 20.

In addition to the parts so far described, the novel spinning machine may include funnels 54

adjustably mounted by means of suitable clamps 55 on the cross-beam 28 of the frame 10 and located beneath and in registry with the drawing rolls 22 and 23 to catch any drippings therefrom. Troughs 56, conveniently mounted on the cross-beam 28 of the frame 10, are located in receiving relation to the funnels 54 to receive the drippings therefrom and to dispose of the same in any suitable manner.

The machine furthermore is provided with the customary plurality of ring spindles 57 rotatably mounted on brackets 58 fixed upon the frame 10, said spindles 57 including pulleys 59 whereby they are rotated on their axes; the spindles 57 are designed to receive the customary tubular reels 60 for receiving the spun linen yarn in the conventional manner. The spindles 57 with their pulleys 59 are arranged upon opposite sides of the spinning machine in the customary manner in co-operating relation to the drawing units, and may be operatively connected in groups of four, that is two on each side of the machine with a suitable source of power. The driving power for the spindles 57 may be derived from a conventional operating drum 61 carried by a shaft 62 mounted in suitable bearings 63 conveniently fixed on the frame 10, said shaft 62 being driven in any conventional manner. In such case a band 64 passes around the drum 61 and over a tension pulley 65 and over the pulleys 59 of the group of spindles 57 in the customary manner.

The tension pulley 65 may be arranged to perform its functions in any convenient manner and as shown is mounted on a bracket 66 carried by a member 67. The latter is fixed on a carrier 68 fulcrumed on a rod 69 suitably supported on the frame 10 and is provided with a weight 70 whereby the pulley 65 is caused to automatically maintain the band 64 under the desired tension. Splash boards 71 terminating along their lower edges in troughs 72 are mounted in co-operating relation with the spindles 57 in the well-known way. The spindles 57 project upwardly through the customary rings 73 of a ring spinning machine and include conventional travellers 73^a, said rings 73 as usual being mounted in the conventional fixed ring plates or ring rails 74 supported in position in the machine in any well-known way. Separators 75 such as customarily are embodied in ring spinning machines are arranged and operated in the conventional manner in the novel machine. The latter may further include tubular guides 76 located in operative relation to the feeding cylinders 20 and 21, and guide eyelets 77 in associated relation to the spindles 57 and pivotally mounted at 78 upon a bracket rail 79 suitably supported upon the cross-beam 28 of the frame 10.

In the operation of the novel ring spinning machine the partly degummed rovings are unwound from the immersed cheeses 12 and pass over the porcelain guides 16 and 17 through the tubular guides 76 to the feeding rolls 20 and 21, which serve to continuously feed the rovings to the drawing rolls 22 and 23.

Because of the relatively shallow and easy undulating form of the grooves of the feeding rolls 20 and 21, the latter develop the strong gripping forces on the partly degummed rovings which are required to efficiently cooperate with the intensive drawing forces which are exerted on the rovings, without however at any time bending the fibrils sufficiently to break or otherwise injure the same. At the same time, the

rolls 20 and 21 grooved as shown and described efficiently grip the large number of fibrils which are present in the aforesaid rovings.

The rovings pass between the drawing rolls 22 and 23 and because of the heavy pressure exerted by the drawing roll 23 are pressed firmly against the grooved peripheral surface of the associate drawing roll 22. As a result the rovings as they pass between the drawing rolls 22 and 23 are securely and firmly gripped without being broken or otherwise injured and without developing any slippage relatively thereto.

The efficiency of the feeding rolls grooved as illustrated and described is in contradistinction to that of the conventionally grooved rolls of customary spinning machines in which the grooving is either such as to be incapable of establishing the strong gripping action which is required, in the instant case, or otherwise to create excessive bending forces which in the novel spinning machine and drawing process would break and otherwise injure the fibrils contained in the rovings.

Because the drawing rolls 22 and 23 are rotated faster than the feed rolls 20 and 21, and because of the fact that the rovings are also firmly and securely gripped between the feed rolls 20 and 21, the rovings are subjected to an intense drawing action over the relatively small distance between the bight of the feed rolls 20 and 21 indicated by the line A—A and the clamping bight of the drawing rolls 22 and 23 indicated by the line B—B which distance is slightly more than the length of the longest cell in the sliver being acted on. Because of this arrangement and as a result of drawing the roving at the aforesaid short distance, the machine is enabled to develop the drawing forces on the cells of the sliver in contradistinction to exerting the customary drawing forces on the fibers and fibrils as is generally the case in conventional spinning machines.

The intense drawing of the cells at the short distance referred to above enables the machine to effectively cause the partly degummed fibers and fibrils and cells to glide on one another on the residual gum remaining in the material as a result of partly degumming said fibers and fibrils and cells. After passing beyond the drawing rolls 22 and 23, the cells stick to each other because they are still gummy so that, as a result of the operation of the spindles, a spun yarn of maximum smoothness and strength is produced. From the drawing rolls 22 and 23 the drawn roving passes through the guide eyelets 77 and through the travellers 73^a to the reels 60 on the spindles 57 and is spun into yarn and wound on the tubes 60 as the spindles 57 with the tubes 60 thereon are rotated in the conventional manner. In its finally spun condition, the yarn comprises a plurality of cells bonded together by the residual external gum of the flax which remains between said cells after the partial degumming thereof. The aforesaid yarn is of maximum strength and smoothness and possesses all of the inherent characteristics of existing linen yarns of the tow type to an equal or superior degree.

It is to be particularly noted that in no other spinning machine is the strong pull developed which is an essential feature of the instant process and machine, and which results at least partly from the fact that the drawing roll 23 exerts a heavy pressure, for instance, in excess of fifty pounds on the contiguous drawing roll 22.

In conventional spinning machines, the draw-

ing rolls draw on loose fibers (i. e., fibers which are only indirectly held by the feed rolls) and so no specific force need be developed, while in the instant machine, the fibers are positively held between the feed rolls and the drawing rolls at the same time, and the latter pull heavily on partly degummed cells, i. e., the drawing process is carried out on the cells.

Although the present invention has been described in conjunction with a preferred embodiment, it is to be understood that modifications and variations may be resorted to without departing from the spirit and scope of the invention, as those skilled in the art will readily understand. Thus it will be observed that instead of flax fibers, any other fibers similar in constitution to flax with respect to cells and gum may be used such as hemp fibers, etc. It further will be obvious that instead of roving, the material may be used in any suitable form in carrying out the novel process. Such variations and modifications are considered to be within the purview and scope of the claims.

I claim:

1. In the art of producing yarn from flax and similar fibers, the process of producing slivers from the non-retted straw of plants which comprises decorticating the non-retted straw to preserve the fibers and to remove the pith, carding said fibers to form the same into slivers, doubling a plurality of slivers to convert the same into a single sliver, combing the latter, passing the combed sliver through a plurality of successive drawing operations and through a roving operation, winding the roving into the form of cheeses, boiling said cheeses in an alkaline solution containing caustic soda to partially remove both the internal gum between the fibrils and the external gum between the fibers to a predetermined degree to cause the fibrils to glide on one another when subjected to a pulling force, and washing said cheeses to remove the caustic.

2. In the art of producing yarn from flax and similar fibers, the process of producing a single sliver from the non-retted straw of plants which comprises decorticating the non-retted straw to preserve the fibers and to remove the pith, carding said fibers to form the same into slivers, combining a plurality of slivers to convert the same into sliver, boiling said sliver in an alkaline solution containing caustic soda to partially remove both the internal gum between the fibrils and the external gum between the fibers to a predetermined degree to cause the fibrils to glide on one another when subjected to a pulling force, and washing said sliver to remove the caustic.

3. The process of producing yarn from flax and

similar fibers which comprises grouping the fibers, partially degumming said grouped fibers to partially remove both the internal gum between the fibrils and cells and the external gum between the fibers to a predetermined extent, subjecting the partially degummed cells of said grouped fibers while the latter are in a wet condition to intense drawing forces of relatively short distance to cause the partly degummed cells in the grouped wet fibers to glide on one another, and spinning said drawn grouped fibers into partly degummed yarn.

4. The process of producing yarn from flax and similar fibers which comprises grouping the fibers and converting the same into slivers, partially degumming said slivers to partially remove both the internal gum between the fibrils and cells and the external gum between the fibers of said slivers to a predetermined extent, subjecting the partially degummed cells in said grouped fibers while the latter are in a wet condition to intense drawing forces of relatively short distance to cause the partly degummed cells in said grouped wet fibers to glide on one another, and spinning the drawn sliver into partly degummed yarn.

5. The method of producing yarn from the fibers of flax and similar plants which comprises grouping said fibers and converting the same into slivers, partially degumming said slivers to partly remove both the internal gum between the fibrils and the external gum between the fibers of said slivers to a predetermined degree, subjecting the partly degummed slivers with the gum remaining therein in a plastic condition to intense drawing forces, and spinning the drawn slivers to convert the same into partly degummed yarn.

6. In the method of producing yarn from the fibers of flax and similar plants, those steps which comprise partially degumming the fibers to a predetermined extent, holding the partially degummed fibers in a wet condition at the feed rolls and the drawing rolls at the same time and exerting a drawing force on the cells within the fibers in said wet condition held between said rolls.

7. In the method of producing yarn from the fibers of flax and similar plants, those steps which comprise partially degumming the fibers to a predetermined extent, gripping the partially degummed fibers in a wet condition at two closely adjacent points simultaneously and exerting a drawing force on the cells within the fibers in said wet condition between said gripping points.

ARTHUR JOB.
